(57) **CLAIM**

The ornamental design for the battery pack, as shown and described.

DESCRIPTION

FIG. 1 is a front isometric view of a first embodiment of a battery pack showing my new design.

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof; and,

FIG. 7 is a bottom plan view thereof.

Any broken lines are for illustrative purposes only and form no part of the claimed design.
